(57) **CLAIM**

The ornamental design for an acorn jewelry bail, as shown and described.

DESCRIPTION

FIG. 1 is a perspective view of an acorn jewelry bail, showing our new design.

FIG. 2 is a front elevational view;

FIG. 3 is a side elevational view, the opposite side view being a mirror image thereof;

FIG. 4 is a rear elevational view, it being understood that the oval shown on the back of the claimed design in FIG. 4 is a slight indentation and not broken line environmental matter; and,

FIG. 5 is a top plan view.
